Application December 15, 1941, Serial No. 423,064

27 Claims. (Cl. 28—21)

This invention relates to a machine for packing and packaging materials. It has for one object to provide a packaging machine for netted fabrics.

Another object is to provide a conveying means for looping and conveying fabrics, netted and otherwise made.

Another object is to provide a machine and a method for laying fabrics, netted or otherwise, into a container and for progressively moving the container with relation to the filling means.

Another object is to provide a mechanical movement for positioning a length of fabric upon a carrier and for moving the fabric to engage members formed on the carrier.

Other objects will appear from time to time throughout the specification and claims.

This invention is illustrated more or less diagrammatically in the accompanying drawings, wherein:

Figure 1 is a front elevation of the machine with parts broken away.

Figure 2 is a side elevation of Fig. 1 with parts broken away and parts in section.

Figure 3 is a horizontal section taken at line 3—3 of Figure 2.

Figure 4 is a sectional detail taken on line 4—4 of Figure 3, showing the container moving means, on an enlarged scale, with parts in elevation.

Figure 5 is a transverse horizontal sectional detail taken at line 5—5 of Figure 4.

Figure 6 is a horizontal section taken at line 6—6 of Figure 2, on an enlarged scale.

Figure 7 is a vertical sectional detail taken on an enlarged scale at line 7—7 of Figure 2.

Figure 8 is a transverse sectional detail taken at line 8—8 of Figure 2 on an enlarged scale.

Like parts are indicated by like characters throughout the specification and the drawings.

The machine of the present invention may be carried on any suitable base or support. As shown, a support 1 is provided which may have feet 2, and these feet are supported on a floor 3 or upon any other foundation or support. Secured to the base 1 are lateral frame members 4, 4, upon which are mounted supporting members 5, 5, and an additional cross member 6 may be positioned upon the member 5. The details of the supporting frame are unimportant, and it is sufficient for the purposes of the invention that means are provided which can carry the necessary parts.

The means for positioning the length of fabric upon the carrier will now be described. The carrier itself comprises a shaft 7 which is carried

in a suitable bearing within the member 8, which is itself supported from the member 1. The shaft may carry a gear 9 by means of which it is driven from a shaft 10 through a pinion 11. The shaft 10 also carries a sprocket 12, which is driven by a chain 13 from a sprocket 14 on a shaft 14. Further details of that drive will be described below. So far as the carrier is concerned, it is driven by the shaft 7 and includes a pulley which may be formed of a single member or may, as in the form here shown, be formed of a series of separate pulley surface members 15, 15, which as shown are somewhat rounded. Positioned on the shaft 7 and at each side of the pulley is a member 16, upon which pins 17 are positioned. The shaft with its members 15 and 16 rotates in the direction of the arrow shown in Figure 2, and the pins 17 are preferably inclined rearwardly with respect to the direction of the rotation.

Associated with the pulley surface members 15 is a set of belts 18, one belt being provided for each member 15. If there were but a single member 15 there might be but a single belt. The belts 18 pass about the belt surface members 15 and pass about idlers 19. At their lower ends they are carried on idler pulleys 20, which are themselves supported on a shaft 21, and this shaft is carried in bearings positioned adjacent the lower end of a plate-like member 22. This plate-like member extends downwardly from any suitable support on the general frame of the machine. The belts 18, after passing about the idlers 20, extend upwardly and pass about idlers 23, which are carried upon a shaft 24, which is itself supported in any suitable bearings.

A second belt or a second set of belts is associated with the belt or belts 18. This includes belts 25. They are driven by contact with the belts 18 or by contact with the material upon those belts. As shown, the belts 25 are in contact with approximately one-half of the surface of the members 15, and they move downwardly substantially parallel to the belts 18 and are guided somewhat by the idlers 23, which also guide the belts 18. At their lower ends the belts 25 are positioned upon and turn about idlers 26, which are carried upon a shaft 27, which is itself supported in suitable bearings at the lower end of a plate 28. This plate 28 is similar to the plate 22 and like it is supported upon any suitable support in the frame structure. The belts 25 pass from the idlers 26 to idlers 29, which are carried upon a shaft 30 adjustably supported in a member 31, which forms a part of or is supported by the main frame. The

belts 25 thence move about idlers 32, carried on a shaft 33, which is supported upon projections 34 from the main frame. The carrier mechanism thus described comprises, therefore, one or more pulleys, about which are mounted two belts or two sets of belts, and the belts are arranged both of them partially to surround the pulley or pulleys and to overlap each other on the pulleys, and they extend from the pulley's substantially parallel path to the container into which the material is to be discharged.

The mechanism for placing the length of fabric upon the pulley system will now be described. The shaft 10, which is driven with the shaft 7 but at higher speed, carries a cam member 35 within which is positioned a roller or shuttle 36. This shuttle is fastened to a member 37, which moves in a guide formed within the member 38. An arm 39 is hinged to the member 37, as at 40. It moves within a guide portion 41 and has an upwardly extending portion 42 at its free end. The portion 42 has a laterally bent arm 43 which terminates at its free end in a ring 44, and the length of fabric or other material 45 passes through the ring 44 which together with the member 39 is moved back and forth in a substantially figure eight (8) pattern. The means for producing this motion will be described below. The fabric strand or length 45, before passing to the ring 44, passes about a fixed pin 46 carried by or positioned upon arms 47 which is secured to any suitable housing member or support, for example, to the enclosing or housing member 48.

Positioned adjacent the arm 39 is a guide plate 49. This guide plate has an irregularly shaped cavity or groove formed in it. This groove includes one-half portion 50 and a similar portion 51. The arm 39 carries a roller 52 which extends into the groove or cavity 50, 51. Movably mounted within the portion 53 upon the pin 53a is a pawl 53. As shown, it is unsymmetrical and is mounted unsymmetrically. A similar pawl 54 is mounted upon a pin 55 within the channel or groove portion 51. One end of a spring 56 is secured to the short end of the pawl 53. This spring is lapped around a pin or projection 57 and its other end 58 extends through a groove 59 and is secured to the lever 60, which itself extends partly into the channel 50 and is pivoted at 61. The spring as shown is positioned outside of the cavity or channel 59. One end of it extends through the slot 59 to engage the lever 60, and the other end extends through a slot 62 to be secured to the short end of the pawl 53.

The spring arrangement just described for the pawl 53 is substantially duplicated for the pawl 54. As shown a spring 63 at one end extends through a slot 64 and is secured to the short end of the pawl 54. The spring is positioned about the pin 65 and at its other end extends through a slot 66 to engage a lever 67. This lever is pivoted at 68 and extends partly into the channel or groove portion 51.

The effect of the cam 35 is to move the arm 39 back and forth and the cooperation of the roller 52 with the pawls 53 and 54 and their associated parts causes the roller to follow the outline of the groove or channel formed by the portions 50 and 51, with the result that it follows, in effect, a figure eight (8) path of movement, and the ring 44 follows, of course, the same path, and in doing so positions the length of fabric upon the pins 17. The ring 44 thus

moves upward and about each successive pin 17, first one on the right and then one on the left, or vice versa.

The drive for the mechanism in the form here shown is furnished by a motor 69 which by means of a gear reduction 70, which need not be shown in detail, drives the shaft 14, upon which the sprocket 14 is positioned. A belt pulley 71 is also positioned on the shaft 14 and by means of a belt 72 drives a drive 73, which includes two bevel pulleys 74, 74, which in turn drive a belt 75 from which a pulley 76 is driven, and this pulley is mounted on a shaft 77. The drive 73 includes members movably mounted on lever 78, journalled at 79, and provided with an adjusting screw 80, which is operated by a handle 81. The purpose of the parts just described is to vary the speed of the drive, and they need not be described in further detail, since variable speed drives are readily available on the market, and their details form no part of the present invention. The shaft 77 rotates in the direction of the curved arrow in Figure 6. Fixed to the shaft 77 is a bevel gear 82 provided with a clutch face 83. Fixed also on the shaft is an oppositely facing bevel gear 84 provided with a clutch face 85. A clutch member 86 is slidably mounted upon the shaft 77 between the bevel gears 82 and 84. It is provided with two clutch faces, and by means of a lever 87 it may be moved into or out of engagement with either of the clutch faces 83 or 85. The lever 87 is pivoted as at 88 and engages the clutch member 86. Its opposite end is received by the pins 89 of a rocker 90, which is pivoted as at 91. A spring 92 is engaged at one end on the rocker and at the other to a housing member 93. An operating lever arm 94 extends outwardly and is received by the pins 95 on a slide member 96. This slide member is carried in bearings 97 and carries one or more adjustable stops 98.

Journalled in the housing 99, which encloses the bevel gears 82 and 84 is a screw shaft 100. Within the housing 99 the screw shaft carries fixed upon it a bevel gear 101, which meshes with the gears 82 and 84, to be driven by them. The shaft 100 is threaded throughout substantially its length, and its free end is supported in a bearing 102. A nut 103 is interiorly threaded and engages the threads of the shaft 100. The nut 103 is secured to or formed integrally with an axle 104 of a dolly. A shaft 105 is positioned within the axle and carries flanged wheels 106, which are arranged to run upon tracks 107, carried by the general frame assembly. Supports 108 extend upwardly from the axle 104 and support at their upper ends a housing assembly 109, within which driving means are mounted. They will be described below. A second pair of supports 110 is also secured at its upper end to the housing assembly 109 and at its lower end carries flanged wheels 111 which also run on the tracks 107.

Adjustably fastened on the track members 107 or the frame members 6 are stops, two of which are shown. Each stop includes a portion 112, which engages the frame member 6 and a portion 113 which has an upward extension 114. They are held together by a bolt 115 and a nut 116. The stop portions 114, when in assembled position, as shown particularly in Figures 6 and 7 and generally in Figure 2, extend into the path of lever 117, which is pivoted at 118 on a frame or plate-like member 119. At its upper end the member 117 has a pair of oppositely disposed

arms 120, and upon each of these is pivoted a dog 121. Springs 122 are mounted on the dogs and serve to move them to the left from the full line position to the dotted line position of Figure 4. The dogs are provided with downward extensions 123 which are positioned to be contacted by knobs or other projections 124 formed on a slide member 125, which is positioned against the plate-like member 119 and movably held in place by keepers 126. At one end the slide 125 is provided with a pin 127, which extends into the slot 128 of an operating lever 129. At its upper end this lever is pivoted at 130 and provided with a handle 131. A member 132 extends in the opposite direction of the handle 131 and carries a pin or projection 133, which may be positioned to contact a shoulder 134, which forms one end of a notch 135, in a controlling member 136. The other end of the notch is formed by an end portion 137. The member 136 is secured to the bottom 138 of a package receiver, which has fixed sides 139 and may have hinged doors or gates 140.

The box or container for the package, which box includes the bottom 138 and associated walls and gates, is movably carried upon four screws 141. Each of these screws is engaged by a nut 142 and each nut is provided on its exterior with gear teeth 143. Each nut, as shown particularly in Figures 3 and 4, meshes with a main gear 144. The four nuts and the main gear are mounted for rotation between the lower housing member 109 and an upper housing member 145, which are separated by spacing parts 146 of suitable thickness properly to position the gears and nuts. The sides of the cavity formed between the plates 109 and 145 may be closed by walls 147. Each of the screws is secured to the bottom 138 of the package carrying box, and each of them extends downwardly through the housing formed by the plates 109 and 145.

The gear 144 is fixed to a shaft 148 at the lower end of which a bevel gear 149 is secured. This bevel gear meshes with a bevel gear 150 on a shaft 151, which is carried in suitable bearings in the frame or is supported upon the member 119 or in any other suitable manner. Fixed to the shaft 151 is a clutch member 152. Slidable on the shaft 151 is a clutch member 153, which is provided with a handle 154, mounted on a crank 155. A collar 156 fixed also on the shaft 151 prevents the member 153 from being removed accidentally from the shaft.

A ratchet wheel 157 is fixed on the shaft 151 in position to be engaged by the dogs 120.

While material may be received into the member 138, 149 in any desired manner, the example which is shown herewith includes paper sheets or sheets 158, which may be positioned about a piece of cardboard or similar material 159, and as a matter of convenience a strip of adhesive tape 160 may be secured to the paper so that upon the completion of the package the parts may be glued or secured together. Frequently another piece of board similar to the board 159 will be put on top of the package. The machine and the method of using it are not limited to any wrapping for the package, and the one shown and just described is merely illustrative of a possible use.

It will be realized that whereas we have described and shown a practical and operative embodiment of our invention and the method for carrying it out, nevertheless many changes may be made in the size, shape, number and disposi-

tion of parts and in the details and steps of such method without departing from the spirit of our invention. We therefore wish our description and drawings to be taken as in a broad sense illustrative or diagrammatic, rather than as limiting use to our precise showing.

Among the modifications which may or may not be present are guides 161 which act as belt strippers to prevent material which has been carried down by the belts 18 and 25 from adhering to them and being carried up by one or the other in its upward movement. They may also serve as means for pressing or ironing down the material which has been deposited into the box or package. The means for moving the arm 39 back and forth may be largely varied and the cam shown is merely one convenient way of doing it. It might, for example, be moved by a crank or in response to a crank motion or to other motion.

The use and operation of the invention are as follows:

As shown in Figures 1 and 2, the box is in the uppermost position ready to receive material. The strand or length of material 45 is shown in Figures 2 and 8 and as there shown has already been passed under the bar 46, the ring 44, and has been engaged upon several of the pins 17. If the mechanism is now started, the belt pulleys 15 and 16 rotate in the direction of the arrow of Figure 2, and by reason of its engagement on the pins 17 the material is carried by the belts and is fed by them finally downwardly into the box. As the belts leave the pulley 15 the material is stripped from the fingers 17 by the belts, so that they may carry it downward to the box.

At the same time that the belt pulley rotates, the member which carries the cam 35 rotates and the shuttle 36 is moved back and forth, carrying the member 37 back and forth within the guide 38.

As this movement takes place, the arm 39 is similarly moved back and forth but its free end is caused to move in a figure-8 pattern, which is shown in detail in Figure 8. Assuming the movement to be in the direction of the full line arrows of Figure 8, the roller 52 will move upwardly along the upper face of the member 54. When it reaches the upper nose of the end of the lever 54 it will depress that end of the lever and at about the same time it strikes the lower end of the lever 67, and moves it outward from the full line position to a position corresponding to the dotted line position of the lever 60. This movement of the member 54 and the lever 67 has moved the spring 63 so that the member 54 is held in the raised position corresponding to the dotted line position of the member 53 as shown in Figure 8.

Continuing its movement, the roller 52 falls down to the lower portion of the channel 51 and at that time its movement is reversed by the shape of the cam 35, and it then travels to the left, meeting the lowered face of the member 53 and moving upward along it. As it moves to the left, and before it strikes the member 53, it must, of course, pass under the lowered end of the member 54. This it does because the spring 63 permits this movement. After passing up the member 53, the roller 52 passes over its end and displaces the lever 62 and moves downwardly to follow the path of the dotted-line arrows, being again reversed in its movement by the cam 35 and moving again up the member 54. Thus the members 53 and 54 and their supports cause the roller 52 to move along the upper side of the cavity 51 when

75 going to the right, to move along its lower side

when going to the left, and to move along the upper side of the cavity 50 when going to the left and to move along the lower side when going to the right, and thus the roller 52 moves in a figure-8 pattern and carries the ring 44 in a figure-8 pattern, so that the length of material which is moving through the ring 44 is progressively looped first about a pin 11 on one side of the apparatus, and next about the next pin 11, on the opposite side of the apparatus. The pins are staggered with relation to each other.

During the movement of the belt and the feeding mechanism just described, the box into which the material is being deposited moves back and forth under the point of discharge of the belts and is progressively moved downward. The means for accomplishing this operation will now be described. The shaft 71 is driven by means of a belt 75 from the adjustable driving assembly which includes the pulleys 73 and 74, the latter being driven by the motor from a belt 72 and through a reduction gearing not shown in detail. The shaft 71 is therefore in rotation at a speed determined by the position of adjustment of the adjusting screw 80. As the shaft 71 rotates, it drives the clutch member 86, and this member may be moved to engage with either the gear 82 or 84. As shown in Figure 6, it is engaged with the gear 84, and through that gear and the bevel gear 101, the shaft 100 is driven, and this shaft, through the nut 103, moves the carriage, which includes the wheels 106 and 111, and the associated frame parts. The direction of this movement depends upon which of the gears 82 or 84 is engaged with the clutch and is therefore driven.

As the carriage moves in either direction, an extension of the shaft 105 will contact one or the other of the stop members 98 on the slide 96 and will move it. As it moves, the adjusting arm 94 of the bell crank is moved, and moves the other arm 90, and through the lever 87 carries the clutch 86 out of connection with the gear 84, and into connection with the gear 82, thus reversing the direction of rotation of the shaft 100, and the carriage and its associated parts back in the opposite direction. This cycle of back and forth movement occurs as long as the mechanism is driven.

In addition to the back and forth drive of the carriage, means are provided for progressively lowering the box which receives the material deposited from the belts. This includes a plurality of threaded shafts 141, each of which is secured to the bottom of the box and each of which is threaded into a pinion 142. These pinions mesh with a main gear 144. As the latter is driven, the pinions are rotated and the screw shafts 141 are moved up or down, depending upon the direction of rotation of the interiorly threaded pinions 142. One means for driving the main gear 144 includes the bevel gears 149 and 150, and the shaft 151. Upon that shaft is mounted a ratchet wheel 157, and the teeth of this wheel may be engaged by the dogs 121. These dogs are carried on the member 117, which is pivoted on the carriage, and as the carriage moves back and forth, the member 117 contacts one of the stops 114 at each end of its excursion. When it does that, it is tilted, and carries one or the other of the dogs 121 upward sufficiently to rotate the ratchet 157 and its rotation rotates the shaft 151, the gears 150 and 149, and finally the main gear 144, and through it the pinions 142. Thus with each re-

versal of direction of the carriage, the box is lowered a predetermined distance. The stops are adjustable and the amount of rotation given the ratchet 157 with each reversal of direction may be varied.

Means are also provided for lowering the box rapidly. These means are shown generally in Figure 2 and in greater detail in Figures 4 and 5. When it is desired to lower the box rapidly, the handle 131 is carried to the position shown in Figure 4, and the slide 125 is moved to the left. The pins 124 carried by the slide contact the arms 123 of the dogs 121 and hold them out of engagement with the ratchet 157. When that is done, the clutch members 152 and 153 on the shaft 151 may be engaged, and then the handle 154 is rotated, and through it the shaft 151 is driven in whichever direction the operator wishes. Spring means not shown may be applied to hold the handle 131 in whatever position the operator desires.

Frequently, however, the weight and friction of the parts will hold themselves in whatever position they are moved to.

After the box has been carried to its lowest position—i. e. after it has been filled—the mechanism is stopped for a moment, the package is closed, completed, and removed, and paper or card board or other material for receiving a subsequent quantity of material is inserted. One material which is particularly well handled by this machine is netting and packages of a given weight are made and the net is not severed between the packages, so that in effect any desired number of packages of netting, each containing a specified quantity, may be made and will remain together. Thus if the netting is packaged 5 pounds to the package, and a purchase made of 25 pounds of netting, the purchaser will buy 5 packages, which are all together, and in using the net he may desire to use only 5 pounds at a time, in which case he will cut off one package, or he may desire to use 15 pounds at a time, and in that case he will cut off three packages.

Since the length of material is laid in between the belts in a strand which runs back and forth across the width of the belts, it will of course be deposited from the belts in the same manner, and the length of material is thus deposited in the box in a continuous strand running back and forth across the box, and these strands are successively laid down from end to end of the box or package. As the material is deposited into the box it is not twisted, and thus as the package is made, no twist is imparted to the material. Where in the specification and claims it has been stated that the belts are parallel to each other for a portion of their travel, it is to be understood that they need not be absolutely parallel. They could move along straight lines as shown in Figure 2 after they leave the drum, or they could move along curved paths so long as they remain close enough to each other to hold and to carry the strands of the material which has been positioned between them. For ordinary mechanical convenience it is usually simpler to guide them so that they move along straight and parallel paths, but they might move along paths of any shape so long as they are held close enough to each other to carry the strands of material. Therefore where the expression "parallel" occurs in the claims it is to be understood as meaning that the belts are guided along identical or similar paths, whatever the shape of the paths, so that for a substantial distance the two

belts run in a relatively constant distance from each other. They may, of course, be in contact with each other.

We claim:

1. In a mechanism for packaging stranded material, a drum, a plurality of rows of pins fixed thereto, and means for carrying a continuous strand of material alternately about a pin, first on one side of the drum and then on the other, a plurality of belts positioned about said drum, and adapted to engage said continuous strand as it passes about said drum, guide means for said belts whereby they are held parallel to each other during a portion of their travel.

2. In a mechanism for packaging stranded material, a drum, a plurality of rows of pins fixed thereto, and means for carrying a continuous strand of material alternately about a pin, first on one side of the drum and then on the other, a plurality of belts positioned about said drum, guide means for said belts whereby they are held parallel to each other during a portion of their travel, and a container positioned to receive material discharged from said belts, and means for moving said container back and forth during the discharge of material, and additional means for progressively lowering said container as material is fed into it.

3. In a mechanism for packaging stranded material, a drum, a plurality of rows of pins fixed thereto, and means for carrying a continuous strand of material alternately about a pin, first on one side of the drum and then on the other a plurality of belts positioned about said drum, guide means for said belts whereby they are held parallel to each other during a portion of their travel, and a container positioned to receive material discharged from said belts, and means for moving said container back and forth during the discharge of material, and additional means for progressively lowering said container in response to its back and forth movement as material is fed into it.

4. In a mechanism for packaging stranded material, a drum, a plurality of rows of pins fixed thereto in staggered position with relation to each other, and means for carrying a continuous strand of material alternately about a pin, first on one side of the drum and then on the other, a plurality of belts positioned about said drum and driven thereby, one belt resting upon the other during a portion of its travel about the drum, guide means for said belts whereby they are held parallel to each other during a portion of their travel, and a container positioned to receive material discharged from said belts, and means for moving said container back and forth during the discharge of material, and additional means for progressively lowering said container as material is fed into it.

5. In a mechanism for packaging stranded material, a drum, a plurality of rows of pins fixed thereto in staggered position with relation to each other, and means for carrying a continuous strand of material alternately about a pin, first on one side of the drum and then on the other, a plurality of belts positioned partially about said drum and driven thereby, one belt resting upon the other during a portion of its travel about the drum, guide means for said belts whereby they are held parallel to each other during a portion of their travel, and a container positioned to receive material discharged from said belts, and means for moving said container back and forth during the discharge of material, and additional means

for progressively lowering said container as material is fed into it.

6. In a mechanism for packaging stranded material, a drum, a plurality of rows of pins fixed thereto in staggered position with relation to each other, and means for carrying a continuous strand of material alternately about a pin, first on one side of the drum and then on the other, a plurality of belts positioned partially about said drum and driven thereby, one belt resting upon the other during a portion of its travel about the drum, guide means for said belts whereby they are held parallel to each other during a portion of their travel, guides adjacent the discharge ends of said belts to separate material from said belts, and a container positioned to receive material discharged from said belts, and means for moving said container back and forth during the discharge of material, and additional means for progressively lowering said container as material is fed into it.

7. In a mechanism for packaging stranded material, a drum, a plurality of rows of pins fixed thereto in staggered position with relation to each other, and means for carrying a continuous strand of material alternately about a pin, first on one side of the drum and then on the other, a plurality of belts positioned partially about said drum and driven thereby, one belt resting upon the other during a portion of its travel about the drum, guide means for said belts whereby they are held parallel to each other during a portion of their travel, guides adjacent the discharge ends of said belts to separate material from said belts, and a container positioned to receive material discharged from said belts, and means for moving said container back and forth during the discharge of material, and additional means for progressively lowering said container as material is fed into it.

8. In a machine for forming packages of material, a material receiving container, and means for feeding a strand of material to said container, said means including a drum, a plurality of pins positioned on opposite sides of said drum, and a feeding mechanism, said mechanism including a guide and means for moving it back and forth between said pins, whereby material moving past said guide is guided back and forth and is looped upon said pins, and a plurality of belts, said belts adapted to receive material from said pins and to deposit it into said container.

9. In a machine for forming packages of material, a material receiving container, and means for feeding a strand of material to said container, said means including a drum, a plurality of pins positioned on opposite sides of said drum, and a feeding mechanism, said mechanism including a guide and means for moving it back and forth between said pins, whereby material moving past said guide is guided back and forth and is looped upon said pins, and a plurality of belts, said belts adapted to receive material from said pins and to deposit it into said container, and additional guides adjacent the discharge ends of said belts, adapted to prevent material from being carried out of the container by the belts.

10. In a machine for forming packages of material, a material receiving container, and means for feeding a strand of material to said container, said means including a drum, a plurality of pins positioned on opposite sides of said drum, and a feeding mechanism, said mechanism in-

cluding a guide and means for moving it back and forth between said pins, whereby material moving past said guide is guided back and forth and is looped upon said pins, and a plurality of belts, said belts adapted to receive material from said pins and to deposit it into said container, and guides for said belts adapted to cause them to move during a portion of their travel along parallel paths, and additional guides adjacent the discharge ends of said belts, adapted to prevent material from being carried out of the container by the belts.

11. In a machine for forming packages of material, a material receiving container, means for moving it back and forth, and means for progressively lowering it, and means for feeding a strand of material to said container, said means including a drum, a plurality of pins positioned on opposite sides of said drum, in staggered position with relation to each other, and a feeding mechanism, said mechanism including a guide and means for moving it back and forth between said pins, whereby material moving past said guide is guided back and forth and is looped upon said pins, and a plurality of belts, said belts adapted to receive material from said pins and to deposit it into said container.

12. In a machine for forming packages of material, a material receiving container, means for moving it back and forth, and means for progressively lowering it, and means for feeding a strand of material to said container, said means including a drum, a plurality of pins positioned on opposite sides of said drum, in staggered position with relation to each other, and a feeding mechanism, said mechanism including a guide and means for moving it back and forth between said pins in a substantially figure-8 pattern, whereby material moving past said guide is guided back and forth and is looped upon said pins, and a plurality of belts, said belts adapted to receive material from said pins and to deposit it into said container.

13. In a machine for forming packages of material, a material receiving container, means for moving it back and forth, and means for progressively lowering it, and means for feeding a strand of material to said container, said means including a drum, a plurality of pins positioned on opposite sides of said drum, in staggered position with relation to each other, and a feeding mechanism, said mechanism including a guide and means for moving it back and forth between said pins in a substantially figure-8 pattern, whereby material moving past said guide is guided back and forth and is looped upon said pins, and a plurality of belts positioned partially about said drum, and one resting upon the other, said belts adapted to receive material from said pins and to deposit it into said container.

14. In a machine for forming packages of material, a material receiving container, means for adjusting its position, means for moving it back and forth, and means for progressively lowering it in response to such back and forth movement, and means for feeding a strand of material to said container, said means including a drum, a plurality of pins positioned on opposite sides of said drum, in staggered position with relation to each other, and a feeding mechanism, said mechanism including a guide and means for moving it back and forth between said pins in a substantially figure-8 pattern, whereby material moving past said guide is guided back and forth and is looped upon said pins, and a plu-

rality of belts positioned partially about said drum, and one resting upon the other, said belts adapted to receive material from said pins and to deposit it into said container, and guides for said belts adapted to cause them to move during a portion of their travel along parallel paths, and additional guides adjacent the discharge ends of said belts, adapted to prevent material from being carried out of the container by the belts.

15. In combination in a packaging machine, a container, means for moving it back and forth, and means for lowering it, and means for depositing material into said container, said means including a plurality of belts, and means for laying material transversely between said belts, said means including a looper, and means for carrying said looper back and forth transversely of said belts, and means for receiving the material from said looper, and for carrying it, substantially undisturbed, to a point between said two belts.

16. In combination in a packaging machine, a container, means for moving it back and forth, and means for lowering it, and means for depositing material into said container, said means including a plurality of belts, and means for laying material transversely between said belts, said means including a looper, and means for carrying said looper back and forth transversely of said belts, and for causing it to move in a figure-8 pattern, and means for receiving the material from said looper, and for carrying it, substantially undisturbed, to a point between said two belts.

17. In combination in a packaging machine, a container, means for moving it back and forth, and means for lowering it, and means for depositing material into said container, said means including a plurality of belts, and means causing them to move along parallel paths during a portion of their travel, and means for laying material transversely between said belts, said means including a looper, and means for carrying said looper back and forth transversely of said belts, and for causing it to move in a figure-8 pattern, and means for receiving the material from said looper, and for carrying it, substantially undisturbed, to a point between said two belts.

18. In combination in a packaging machine, a container, means for moving it back and forth, and means for progressively lowering it, and means for depositing material into said container, said means including a plurality of belts, and means for laying material transversely between said belts, and laying means including a looper, and means for carrying said looper back and forth transversely of said belts, and means for receiving the material from said looper, and for carrying it, substantially undisturbed, to a point between said two belts.

19. In combination in a packaging machine, a container, means for moving it back and forth, and means for progressively lowering it in response to such back and forth movement, and means for depositing material into said container, said means including a plurality of belts, and means for laying material transversely between said belts, and means including a looper, and means for carrying said looper back and forth transversely of said belts, and means for receiving the material from said looper, and for carrying it, substantially undisturbed, to a point between said two belts.

20. In combination in a packaging machine, a container, means for moving it back and forth, and means for progressively lowering it in re-

sponse to such back and forth movement, and means for depositing material into said container, said means including a plurality of belts and means causing them to move along parallel paths during a portion of their travel, and means for laying material transversely between said belts, said means including a looper, and means for carrying said looper back and forth transversely of said belts, and for causing it to move in a figure-8 pattern, and means for receiving the material from said looper, and for carrying it, substantially undisturbed, to a point between said two belts.

21. In a mechanism for packaging stranded material, a drum, a plurality of rows of pins fixed thereto, and means for carrying a continuous strand of material alternately about a pin, first on one side of the drum and then on the other, a plurality of belts positioned about said drum, and adapted to engage said continuous strand, as it passes about said drum.

22. In a mechanism for packaging stranded material, a drum, a plurality of rows of pins fixed thereto, and means for carrying a continuous strand of material alternately about a pin, first on one side of the drum and then on the other, a plurality of belts positioned about said drum, and a container positioned to receive material discharged from said belts, and means for moving said container back and forth during the discharge of material, and additional means for progressively lowering said container as material is fed into it.

23. In a mechanism for packaging stranded material, a drum, a plurality of rows of pins fixed thereto, and means for carrying a continuous strand of material alternately about a pin, first on one side of the drum and then on the other, a plurality of belts positioned about said drum, and adapted to engage said continuous strand, as it passes about said drum, and means for causing said belts to run together during a portion of their travel.

24. In a mechanism for packaging stranded material, a drum, a plurality of rows of pins fixed thereto, and means for carrying a continuous strand of material alternately about a pin, first on one side of the drum and then on the other, a plurality of belts positioned about said drum, and means for causing said belts to run together during a portion of their travel, and a container positioned to receive material dis-

charged from said belts, and means for moving said container back and forth during the discharge of material, and additional means for progressively lowering said container as material is fed into it.

25. In a mechanism for packaging stranded material, a drum, a plurality of rows of strand engaging projections fixed on said drum, means for rotating said drum, and means for carrying a continuous length of material, and for alternately looping said material, first about a projection of one row and then about a projection of the other row, and a plurality of belts positioned one above the other, and each mounted to move about said drum, the two belts together being adapted to engage said continuous strand between themselves as it is passed about said drum.

26. In a mechanism for packaging stranded material, a drum, a plurality of rows of strand engaging projections fixed on said drum, means for rotating said drum, and means for carrying a continuous length of material, and for alternately looping said material, first about a projection of one row and then about a projection of the other row, and a plurality of belts positioned one above the other, and each mounted to move about said drum, the two belts together being adapted to engage said continuous strand between themselves as it is passed about said drum, and means for guiding said belts to cause them to move along parallel paths after they have left said drum.

27. In a mechanism for packaging stranded material, a drum, a plurality of rows of strand engaging projections fixed on said drum, means for rotating said drum, and means for carrying a continuous length of material, and for alternately looping said material, first about a projection of one row and then about a projection of the other row, and a plurality of belts positioned one above the other, and each mounted to move about said drum, the two belts together being adapted to engage said continuous strand between themselves as it is passed about said drum, and guide means causing said belts to move after they have left said drum along similarly shaped paths whereby the distance between them is maintained substantially constant until their point of discharge is reached.
